[57] CLAIM

The ornamental design for a basketball possession indicator, as shown and described.

DESCRIPTION

FIG. 1 is a perspective view of a basketball possession indicator showing my new design;

FIG. 2 is a right side elevational view of the design as seen in FIG. 1; and

FIG. 3 is a rear elevation view of the design as seen in FIG. 1, the bottom being plain and unornamental.

FIG. 1

FIG. 2

FIG. 3
